UNITED STATES PATENT OFFICE.

GERMAIN LEPAGE, OF TIVERTON, RHODE ISLAND, ASSIGNOR OF ONE-HALF TO HIMSELF AND ONE-HALF TO JOSEPH P. LE PAGE.

LOOM-TEMPLE.

1,324,163.

Specification of Letters Patent.

Patented Dec. 9, 1919.

Application filed May 7, 1919. Serial No. 295,451.

To all whom it may concern:

Be it known that I, GERMAIN LEPAGE, a citizen of the United States, residing at Tiverton, county of Newport, State of Rhode Island, have invented certain new and useful Improvements in Loom-Temples, of which the following is a specification.

This invention relates to improvements in loom temples and particularly to a re-
10 pair attachment for prolonging the life of a worn or broken temple by a supplementary guiding of the sliding shank outside of the case.

The temple casings ordinarily supplied by the loom manufacturers seem universally to be made of such inferior metal and workmanship that they very rapidly wear out or break and require replacement. The occurrence is such a frequent one in the mills
15 that usually a supply of casings is kept on hand so that replacement may be made as soon as a break-down occurs.

My present improvement follows the principles of my previous Patent No. 1,263-,
25 686, in which I positively guide the shank as distinguished from the mere steadyng of the shank on one side to prevent it from tipping. It will be understood that merely adjustably pressing the slide bar against
30 the old worn bearing in the temple casing affords no permanent relief, but simply tends to complete the wearing away of the bearing and the final breaking of the temple casing itself.

35 My present invention, following that in my prior patent, depends upon the conception of a complete and independent guide for the slide bar outside of the temple casing, as distinguished from those constructions
40 in which adjustable pressers force the slide against the already worn bearing in the casing.

This I accomplish by a guide embracing the shank on three sides in such a manner
45 that it is snugly sustained in proper alignment to the casing and maintained in that position even though the forward end of the casing be broken away as so frequently happens. I thus not only relieve the old
50 worn bearing in the casing from further wear and eventual ruin, by transferring to my shank-embracing guide itself the supporting and guiding function for the forward end of the slide-bar, but obviate the
55 necessity for any adjustment, as has been

contemplated with the devices of others, in which the presser forced the slide bar against the worn bearing and had to be adjusted as the bearing continued to wear away. My device may be applied to temples that have 60 been worn, thus avoiding expensive replacement, and materially prolongs the life of a temple by taking upon itself the full wear of the shank.

The structure and arrangement of my 65 guide will be more fully described in the specification which follows. For the purposes of illustration I have shown in the accompanying drawings two forms of my invention adapted to standard temples now 70 used. Throughout the specification and drawings like reference characters are correspondingly employed. In the drawings:

Figures 1 and 2 show side and plan views, respectively, of a temple equipped with my 75 guide.

Fig. 3 an end view partly in section of the temple and guide.

Fig. 4 a view of the guide removed.
Figs. 5 and 6 show side and plan views, 80 respectively, of a modified form of temple and the form of guide used thereon.

Fig. 7 is an end view thereof, and

Fig. 8 is a perspective view of my guide.

I have indicated at S throughout the several figures of the drawings, the spring-tensioned sliding shank of a loom temple of usual construction, and at C the casing in which the shank slides.

In Figs. 1 to 4 inclusive, I illustrate a 90 form of shank embracing guide or wear shoe of any suitable material, and which I have found highly satisfactory in use as affording a maximum guiding and sustaining surface for the shank designed to relieve the 95 shank bearing in the casing of all wear from any face of the sliding shank by spacing the shank from the casing walls and by guiding and preventing lateral shifting movement of the shank.

The guide shown in these figures consists of a member preferably of one-piece construction, providing a relatively flat attaching surface 1, adapted to be secured to the bottom of the casing C, a wear surface 2 rising from said surface 1, and over which the shank slides and by which it is spaced from the bottom wall of the case, and a pair of upright guiding surfaces 3, one on either side of said wear surface 2, and adapted to 110

embrace the vertical lateral faces of the shank, to guide it in its movement and to prevent lateral shifting thereof. The shoe may be suitably strengthened as by one or 5 more ribs 4.

The surfaces 2 and 3 provide a way through which the shank slides in movement defined and wear received relation, and by reason of this construction, I avoid the 10 necessity of providing an adjustment for the guide, as is necessary when the guide simply presses the shank closely to the worn bearing.

In Figs. 5 to 8 inclusive, I illustrate a 15 modification designed for use with a temple case of older type in which the shank S has its greater dimension transversely (viewing the shank in plan as shown in Fig. 6.) In these figures, the surface 2 takes the wear 20 of one of the lateral faces of the shank and the furcations 3 embrace the top and bottom faces of the shank.

In both forms, the bifurcated construction provides a guide embracing the shank on 25 three sides and not only spacing the shank from contact with the walls of the casing C, but positively defining and guiding the shank in its movements and preventing all tendency of it to shift laterally (Figs. 1 to 30 4) or vertically (Figs. 5 to 8.)

Various other modifications in the form

and construction of my device may obviously be resorted to, all without departing from the spirit of my invention if within the limits of the appended claims.

35

What I therefore claim and desire to secure by Letters Patent is:

1. In combination with the sliding shank of a loom temple and its case, a member secured to said case beyond the end thereof 40 and engaging said shank on three sides thereof.

2. A guide and support for the sliding shank of a loom temple, comprising a member mounted beyond the end of the casing 45 in which the shank slides and having a way alined with the guides of the loom temple and supporting said slide in alinement therewith.

3. A guide and support for the sliding 50 shank of a loom temple, comprising a shoe mounted beyond the end of the case in which the shank slides and bifurcated to provide a way through which the shank slides in supported and guided relation to the walls 55 of the case.

In testimony whereof I affix my signature in presence of two witnesses.

GERMAIN LEPAGE.
